Roebuck and Co., Chicago, Ill., a corporation of
New York

Application May 14, 1948, Serial No. 146,369

Term of patent 3½ years

(Cl. D26—14)

To all whom it may concern:

Be it known that I, Wesley E. Kidd, a citizen of the United States and a resident of Glen Ellyn, in the county of Du Page and State of Illinois, have invented a new, original, and ornamental Design for a Phonograph Needle, of which the following is a specification, reference being had to the accompanying drawing, forming a part thereof.

Fig. 1 is a side elevational view of a phonograph needle, showing my new design.

Fig. 2 is a frontal elevational view of the needle illustrated in Fig. 2; and

Fig. 3 is a plan view of the needle illustrated in Figs. 1 and 2.

I claim:

The ornamental design for a phonograph needle, substantially as shown.

WESLEY E. KIDD.
